UNITED STATES PATENT OFFICE.

LONGLEY LEWIS SAGENDORPH, OF CINCINNATI, OHIO, ASSIGNOR OF ONE-HALF TO HARLAN P. LLOYD, OF SAME PLACE.

CLEAT FOR METAL ROOFING.

SPECIFICATION forming part of Letters Patent No. 372,931, dated November 8, 1887.

Application filed August 18, 1887. Serial No. 247,311. (No model.)

To all whom it may concern:

Be it known that I, LONGLEY LEWIS SAGENDORPH, a resident of Cincinnati, in the county of Hamilton and State of Ohio, have invented 5 certain new and useful Improvements in Cleats for Metal Roofing, of which the following is a specification.

The object of my invention is to provide a 10 cleat for securing together sheets of metal roofing, which shall be more durable and render the connection more secure than when connected in the old way by a single-tongued cleat.

In the accompanying drawings, Figure 1 is 15 a section showing two sheets of metal roofing in position before being clamped and provided with my improved cleat. Fig. 2 is a view in perspective of my invention as preferably constructed. Fig. 3 is a plan view 20 showing a sheet of metal from which the cleat is stamped or cut, the dark lines showing the position of the cuts and the dotted lines showing the bent portions of the cleat when in position. Fig. 4 is a view in elevation of one 25 form of cap for covering the joints. Fig. 5 is a view in perspective of parts of two sheets of metal roofing before being clamped and provided with the cap and my improved cleat, one tongue of said cleat being shown in position before bending.

30 My invention consists in stamping or cutting out of a suitable piece of metal a cleat substantially as shown in Fig. 2, and consisting of the two flanges A A', tongues B, and loop C.

The mode in which my improved cleat is applied to a roof is as follows: Having properly secured one sheet of the roof to the sheeting, the looped portion C of the cleat is placed 35 over the flange d of the sheet thus secured, after which the flange A of the cleat is nailed to the sheeting. The flange A being thus secured, the adjoining sheet of metal is placed over this flange, the flange d of this latter sheet fitting up against the loop C of the cleat. The two flanges d of the adjacent sheet of roofing being in position, the cap E is then placed 40 over the two flanges d and over loop C of the

cleat, as shown in Fig. 5. The cap being placed in position, the tongues B are bent 50 down over the cap and clamped thereto, thus securely locking the two flanges of adjoining sheets and forming a perfectly water-tight joint.

The advantages of my improved cleat over 55 the old single-tongued cleat are that, in addition to its cheapness of manufacture, double security is rendered. If one tongue of the cleat should from any cause become broken, the other tongue will hold the cap securely in 60 position. The loop C, being covered, is not liable to be broken in any way. As constructed, these cleats may be stamped out and shipped in a compact form, and bent when 65 desired for use.

Any desired number of these cleats may be used for properly securing the sheets of roofing; but, as is apparent, only one-half the number of cleats need be used for obtaining the 70 same strength of connection as in the old way when my two-tongued cleat is employed.

If desired, three or more tongues may be employed, the object being to have the tongues located at the outer edges of the cleat.

The flange A' may be left to extend outward 75 at an angle from the body of the cleat, but is preferably bent upward on the inner side, as shown, in order to stiffen the lower edge of the cleat.

What I claim as new, and desire to secure by 80 Letters Patent, is—

1. A roofing-cleat having the tongues B, 85 loop C, and flanges A A', the whole being stamped or cut in one piece of metal, substantially as set forth.

2. The combination of flanges d of two adjoining sheets of roofing, cap E, tongues B, loop C, and flanges A A', the cap E overlapping the flanges d and loop C, and the tongues B overlapping the cap E, substantially as 90 shown and set forth.

LONGLEY LEWIS SAGENDORPH.
